UNITED STATES PATENT OFFICE.

EDWIN GERARD LANCASTER, OF CHICAGO, ILLINOIS.

INTERNAL-COMBUSTION ENGINE.

1,229,761.

Specification of Letters Patent. Patented June 12, 1917.

Application filed May 15, 1913. Serial No. 767,801.

To all whom it may concern.

Be it known that I, EDWIN GERARD LANCASTER, a citizen of the United States of America, residing at Chicago, in the county 5 of Cook and State of Illinois, have invented a new and useful Internal-Combustion Engine, of which the following is a description, reference being had to the accompanying drawings, forming a part of this specification, in which similar letters and numerals of reference refer to similar parts.

My invention relates to internal combustion engines and more particularly to such type thereof as operate in one part in accordance with the principle of a two stroke cycle engine and in another part in accordance with the principle of a four stroke cycle engine and the object of my invention is to provide for that part of my engine, operating 15 in accordance with the principle of a two stroke cycle, at the end of each power stroke, an ample blast of pure air for scavenging and cooling purposes and to introduce into the same cylinder immediately 20 thereafter, a predetermined amount and quality of explosive mixture.

I obtain this object by providing better and more ample means than are used in ordinary two stroke cycle engines for supplying 25 scavenging blasts as well as explosive charges to that part of my engine operating in accordance with the principle of a two stroke cycle, and especially by providing the other part of my engine, operating in accordance with the principle of a four stroke cycle, with closed crank chambers employed 35 as compressors of air or of explosive charges or of both.

In the drawings.

40 Figure 1 is a vertical longitudinal section through my preferred three cylinder engine.

Fig. 2 is the same section as Fig. 1, partly broken off and with the crankshaft 10 turned 180 degrees.

45 The engine illustrated in Figs. 1 and 2 comprises two four stroke cycle cylinders F and F¹ and one two stroke cycle cylinder T, the pistons of all three cylinders being connected to a single crank shaft 10 connected in 50 turn by means of gear wheels g, g¹, a connecting rod 11 and a rocker shaft 12 with cams 13 13¹ to exhaust valves E, E¹ of the four stroke cycle cylinders F and F¹. The latter cylinders are provided in the usual well

known way with inlet valves 14, 14 and in- 5 close pistons P and P¹ respectively. These pistons are connected to cranks 20 and 21 respectively, and both of these two cranks are placed at an angle of 180° in relation to the crank 22 connected to the piston P² within 60 the two stroke cycle cylinder T. Crank cases C, C¹ and C² are connected in some suitable way to the cylinders F, F¹ and T and inclose the cranks 20, 21 and 22 respectively. I¹ is an air inlet into the crank case 65 C¹ and I is an inlet for explosive or combustible mixture into the crank case C. The inlet I is assumed to be connected to a suitable source of explosive and combustible mixture in gaseous form. The crank cases C and C¹ may be connected to the crank case C² through ports O and O¹ provided in the pistons P and P¹ respectively, and through canals 15, 70 16 and 18 arranged between the cylinder T and the two cylinders F and F¹. The crank case C² may be connected through a port O² provided in the piston P² and through canals 16 and 17 to the cylinder T from which the burned expanded gases may be discharged through the exhaust port 19. The 75 ports O and O¹ register in the extreme outer position of the pistons P and P¹ with the canals 18 and 15 respectively, as shown in Fig. 2. Within the piston P² of the cylinder T are provided two deflectors d and d¹, the deflector d for deflecting a current of explosive mixture from the canal 18 toward the bottom of the crank case C², and the deflector d¹ for deflecting a current of pure air from the canals 15 and 16 toward the top of and 80 inside of the hollow piston P². The pistons P and P¹ in moving from their inner position, indicated in Fig. 1, to their outer position, indicated in Fig. 2, compress a charge 85 of explosive mixture and a charge of pure air respectively and deliver these charges into the bottom of the crank case C² and into the top of the hollow piston P² respectively at the instant that the ports O and O¹ register with the canals 18 and 15 respectively. 90 Assuming that each of the three pistons P, P¹ and P² effects an equal displacement during its stroke, the total volume of the three crank cases C, C¹ and C², not including the volume of the displacement of the 95 three pistons P, P¹ and P², is, during the preceding stroke of said three pistons, increased by the displacement of the pistons P 100 105

and P^1 whereby the total volume is reduced by the difference between increase and reduction, *i. e.* by the volume of one piston displacement and that in consequence the total volume of gaseous contents within the three crankcases of C , C^1 and C^2 is already compressed to some degree at the instant that the two pistons P and P^1 have arrived at the end of their out stroke with the piston P^2 at the end of its instroke. The volume of gases contained in the crank case C^2 is thereafter further compressed by the out-stroke of the piston P^2 so that after the exhaust port 19 has been uncovered and a part of the previously burned and expanded gases have been exhausted from the cylinder T , a new charge is forced into the latter as soon as a communication between the cylinder T and the crank case C^2 is effected by an uncovering of the port 17 and by a registering of the port O^2 with the canal 16, as indicated in Fig. 1. As the hollow piston P^2 for the greater part, contains only pure compressed air, this air enters through the port O^2 into the cylinder T in advance of the explosive charge following from the bottom of the crank case C^2 . The advancing charge of pure air expels the waste gases from the cylinder T , cools the inside surface of the walls of the latter and by being interposed between the hot waste gases and the new explosive charge prevents a premature ignition of the latter. The new explosive charge is compressed within the cylinder T by the instroke of the piston P^2 , then ignited in the usual way, preferably by means of an electric igniter L and thereafter expanded by the out stroke of said piston.

The four stroke cycle cylinders F and F^1 operate in the ordinary, well known way with the exception that these cylinders are provided with closed crank cases which are connected to the two stroke cycle cylinder T and operate as described.

After every delivery of a new charge from the crank case C^2 into the cylinder T through the canals 16 and 17, the latter are occupied by combustible mixture, a deflector K is provided between the canals 15 and 16 in such a way that this combustible mixture is forced back from the canals 16 and 17 into the crankcase C^2 as soon as and whenever pure air is admitted through the port O^1 and canal 15, the combustible mixture flowing in advance of the pure air through the hollow piston P^2 toward the bottom of crank case C^2 .

A check valve i may be provided for admitting an explosive mixture into the crankcase C^2 during the instroke of the piston P^2 . With this additional device the gaseous contents of the crankcase C^2 are kept at a minimum pressure equal or nearly equal to that of the source of said mixture and the total charge delivered into the cylinder T is thus

further increased so as to correspond to the displacement caused by a stroke of all three pistons P , P^1 and P^2 .

However, I do not limit myself to the combination of three cylinders as illustrated in Fig. 1. The arrangement of three cylinders has the advantage that four explosions occur at regular intervals during each two revolutions of the crankshaft, namely one explosion in each of the two cylinders F and F^1 and two explosions in the cylinder T .

It will be noticed that the pistons P and P^1 of the two four stroke cycle cylinders have sufficient length so that canals 15 and 18 are constantly covered except at the time that the ports O^1 and O register with said canals respectively.

I desire to claim:

1. In an internal combustion engine, two combustion cylinders, a crankshaft, two separate closed crankcases each connected to one of said cylinders, two pistons each connected to said crankshaft, and also operatively connected to one of said two cylinders, means of communication connecting both of said crankcases with one of said cylinders, said two pistons and said means constructed to deliver charges of gaseous fluid at predetermined periods, from both of said crankcases into one of said cylinders, and means for supplying fuel and air to the other of said cylinders.

2. In an internal combustion engine, two combustion cylinders, one constructed for a two stroke and the other for a four stroke thermo-dynamic cycle, a common crankshaft, two closed crankcases each one in connection with one of said cylinders, means of communication connecting said two crankcases with each other and with the two stroke cycle cylinder, a piston in each of said cylinders, connected to said crankshaft, constructed to deliver, at predetermined periods, charges of gaseous fluid from both of said crankcases to said one of said cylinders, and means for supplying air and fuel to the other of said cylinders.

3. In an internal combustion engine, the combination of one two stroke cycle cylinder with two four stroke cycle cylinders, a closed crankcase connected to each of said four stroke cycle cylinders, a third crankcase connected to said two stroke cycle cylinder, means of communication connecting said crank cases of said four stroke cycle cylinders with said crankcase of said two stroke cycle cylinder and the latter to said two stroke cycle cylinder, three pistons, one of each of said cylinders, and constructed to deliver, in conjunction with said means, periodic charges of gaseous fluid from said four stroke cycle crankcases into said two stroke cycle crankcase and from the latter into said two stroke cycle cylinder.

4. In an internal combustion engine, two

- combustion cylinders, one a four stroke cycle and the other a two stroke cycle cylinder, a crankshaft, a separate crankcase for each of said cylinders, a conduit adapted for intermittent communications with each of said crankcases and with said two stroke cycle combustion cylinder, and pistons operatively connected to said cylinders and said crankshaft and constructed alternately to establish and interrupt said communications. 30
5. In an internal combustion engine, two combustion cylinders, a first one constructed to operate at a four stroke and a second one to operate at a two stroke cycle, a crankshaft, a first and a second separate closed crankcase connected to said first and to said second cylinder respectively, means of communication between said crankcases and between said two stroke cycle crankcase and 40 its appertaining cylinder, two pistons operatively connected to said cylinders and crankshaft and constructed to deliver air at predetermined intervals from said first into said second crankcase and explosive gaseous fluid 45 from the latter into its appertaining cylinder. 50
6. In an internal combustion engine, two combustion cylinders, one a four stroke cycle and the other a two stroke cycle cylinder, a
- separate crankcase for each of said cylinders, a conduit adapted for intermittent communication with each of said crankcases and with said two stroke cycle combustion cylinder and means alternately to establish and interrupt said communications. 35
7. In an internal combustion engine, a first and a second four stroke cycle combustion cylinder, a two stroke cycle third combustion cylinder between said first and said second cylinder, a crankshaft, a first, a second and a third separate closed crankcase connected to said first, second and third cylinder respectively, three pistons operatively connected to said cylinders and crankshaft and constructed to deliver air into said third crankcase from said first and a gaseous combustible from said second crankcase at predetermined intervals and to deliver working charges from said third crankcase into said third cylinder at periods intermediate thereto. 45

In witness whereof I have hereunto set my hand.

EDWIN GERARD LANCASTER.
